DOOR CLOSER

Mathias M. Check, Stratford, Pa., assignor to The Yale and Towne Manufacturing Company, Stamford, Conn., a corporation of Connecticut

Filed Jan. 14, 1959, Ser. No. 786,725

6 Claims. (Cl. 16—49)

This invention relates to a door closer, and more particularly, a door closer of the rack and piston type in which the rotation of the shaft in either of opposed directions is adapted to move the piston in one direction so that the door closer is adapted for universal mounting. This, naturally, eliminates the necessity for right and left hand closers.

My invention is particularly directed to means for simplifying the mounting of a door closer of the class described so that it may control left and right hand doors without substantial change or adjustment. As a feature of this part of the invention, the door closer is adapted for mounting on the door frame, or the door jamb as it is sometimes called, the arm of the closer being then suitably connected to the door so as to control the door effectively and simply. The door may open in either of opposed directions, the control of the door being maintained preferably by a part of the arm riding in a rail secured to the side of the door. This last feature is itself of considerable importance.

As a further feature of the invention, the door closer arm is mounted in a novel manner relatively to the closer and the main operating shaft thereof, so as to be readily and easily placed in a left or right hand position without tools and without complex operating means. As a particular feature of this part of the invention, the casing is constructed so that the door closer arm may readily be placed in either of its operating positions prior to the application of the door closer to the door frame.

I have thus outlined rather broadly the more important features of my invention in order that the detailed description thereof that follows may be better understood, and in order that my contribution to the art may be better appreciated. There are, of course, additional features of my invention that will be described hereinafter and which will form the subject of the claims appended hereto. Those skilled in the art will appreciate that the conception on which my disclosure is based may readily be utilized as a basis for the designing of other structures for carrying out the several purposes of my invention. It is important, therefore, that the claims be regarded as including such equivalent constructions as do not depart from the spirit and scope of my invention, in order to prevent the appropriation of my invention by those skilled in the art.

Referring now to the drawings:

FIG. 1 is a section through a door frame taken just above the closer and illustrating its position when applied to control a door mounted for swinging in a clockwise direction.

In FIG. 2, the same door closer is shown applied to an oppositely swinging door.

FIG. 3 is an elevation showing the door closer secured to the door frame and in controlling relation to the door.

FIG. 4 is an end view of the construction shown in FIG. 3.

FIG. 5 is a partial vertical section through the door closer showing its construction.

FIG. 6 is a horizontal section through a part of the door closer, while FIG. 7 is a perspective view of the channel secured to the door and adapted to contain a roller carried by the arm of the closer.

Referring now more particularly to the drawings, and especially FIGS. 5 and 6, the casing of my door closer

2

is designated by reference numeral 10, and mounted within a cylindrical opening in this casing is a conventional piston 11 having rack teeth 12 and 13 for coaction with teeth 14 on a main operating shaft 15. The piston is formed with an extension 16 for guiding a spring 17, it being the function of the spring to press the piston to the extreme right hand position illustrated in FIG. 5, this position corresponding to the closed position of the door. For controlling the closing speed, there is employed a conventional valve 18, the piston having a ball valve 19 that allows free movement of the piston in door opening direction, or to the left from the position of FIG. 5. When the piston moves toward the closed position of FIG. 5, it will move the fluid of the closer past the valve 18, which functions then to control the closing speed. Insofar as I have described my door closer, it is entirely conventional.

The door closer casing 10 is equipped with bracket-like extensions 20 and 21, extension 20 having an opening for a single securing screw 22, while the extension 21 has openings for two securing screws 23. The securing screws 22, 23 secure the extensions 20, 21 to the upper surface of the frame of the door, as is well illustrated in the several figures. Those skilled in the art will appreciate that this is an extremely simple manner in which to secure a door closer in position, particularly since the extensions 20 and 21 are so shaped as to lie directly against the frame, making extremely simple the application of the screws 22, 23.

The upper portion of extension 20 takes a novel form, probably best illustrated in FIGS. 1 and 2. Thus, it is in the form of a substantially triangular abutment 25, the triangular shape being utilized for a purpose that will appear presently.

The upper end 30 of the main door closer shaft 15 earlier referred to, is slabbed to form a substantially rectangularly shaped part, as well seen in FIGS. 1, 2 and 5. The main arm of the door closer is designated by reference numeral 31, and it is formed with an opening 32 adapted to fit over the slabbed end 30 of the shaft 15, so as to rotate integrally with that shaft. For holding the arm on the end 30 of the shaft 15, I utilize novel means comprising a spring member 33 that bears on the arm 31 where that arm is applied to the end 30 of the shaft 15, all as is best shown in FIG. 5. The spring is maintained in position by a screw 34 extending into the door closer casing 10. The spring member 33 is of such form that it will yield to allow an upward tilting movement of the arm 31 relatively to the end 30 of the shaft 15 when the closer 10 is removed from the door frame. The normal machining clearance provided between the opening 32 in the arm 31 and the slabbed end 30 of the shaft 15 during manufacture allows sufficient upward tilting movement of the arm 31 to bring it above the triangularly shaped abutment 25 so that the arm 31 may be moved from the position illustrated in FIG. 1 to the position illustrated in FIG. 2. In other words, the arm 31 is readily adjustable to one side or the other of the abutment 25 when the closer casing 10 is removed from the door frame. This arrangement is utilized to change the operating direction of the door closer, as is well illustrated in FIGS. 1 and 2, and as will be outlined immediately below.

The arm 31 carries at its outer extreme end a roller 35, this roller being adapted to move in the channel 36 of a channel member 37. Channel member 37 is adapted to be secured to the door to be controlled by the closer, as is well illustrated in the several figures, and probably best in FIG. 4. With the arm 31 in its position relatively to the abutment 25 illustrated in FIG. 1, the roller 35 will coact with the channel member 37, as the door swings clockwise in FIG. 1 to rotate the main shaft 15. This

will naturally compress the spring 17 until the door is released, at which time the door will close under the control of the valve 18. Closing effort will, of course, be imparted to the door through roller 35 by arm 31, the roller coacting with the channel 37. It will be obvious that the channel 37 is easily secured to the door and that the arm 31 is readily applied to the channel.

In FIG. 2, the channel 37 is secured to a door adapted to swing counterclockwise. The arm 31 has been moved relatively to the end 30 of the shaft 15 to place it on that side of abutment 25 opposite its position in FIG. 1. Obviously, the roller 35 will now coact with channel 37 to control the closing of the door.

Those skilled in the art will now fully appreciate that my door closer permits universal application to a left or right hand door without adjustment other than a simple movement of the arm 31. The door closer is secured to the door frame in the same manner, regardless of the direction of the door opening. Further, the door closer is so constructed that the movement of the arm 31 relatively to the abutment 25 may be easily performed, the abutment 25 acting as an indicator as well as a limiting member to facilitate application of the closer in its necessary position by someone not skilled in the door closer art. Therefore, my door closer may be installed by anyone equipped with a screw driver to function on any type of door. I believe that the contribution of my invention will now be well understood by those skilled in the art.

I now claim:

1. In a door closer of the class described, a casing, a shaft rotating in said casing and having an upper end extending upwardly out of said casing, an arm fitted on the upper end of the shaft for rotation therewith, energy storing means adapted to be energized for returning a door to closed position, means interconnecting said shaft and said energy storing means for energizing said energy storing means upon rotation of said shaft and arm in either of opposed directions from a predetermined position relatively to said casing whereby said closer may be used on both left and right hand doors, a spring holding said arm on said upper end of the shaft, limit means on said casing extending upwardly into the path of rotation of said arm with said shaft for holding said arm at one side or the other of said predetermined position relatively to said casing, whereby to determine the hand of said closer, and said spring yielding to permit movement of said arm above said limit means, whereupon said arm may be moved to one side or the other of said limit means to change the hand of the closer.

2. In a door closer of the class described, a casing, a shaft rotating in said casing and having an upper end extending upwardly out of said casing, an arm secured to the upper end of the shaft for rotation with said shaft, energy storing means adapted to be energized for returning a door to closed position, means interconnecting said shaft and said energy storing means for energizing said energy storing means upon rotation of said shaft and arm in either of opposed directions from a predetermined position relatively to said casing whereby said closer may be used on both left and right hand doors, an abutment extending upwardly on said casing for preventing rotation of said arm from one side or the other of said predetermined position to the opposite side thereof, and means mounting said arm on said shaft for limited movement upwardly above said abutment whereupon said arm may be moved to one side or the other of said abutment to change the hand of the closer.

3. In a door closer of the class described, a casing, a shaft rotating in said casing and having an upper end extending upwardly out of said casing, an arm fitted on the upper end of the shaft for rotation therewith, energy storing means adapted to be energized for returning a door to closed position, means interconnecting said shaft and said energy storing means for energizing said energy storing means upon rotation of said shaft and arm in

either of opposed directions from a predetermined position relatively to said casing whereby said closer may be used on both left and right hand doors, a spring holding said arm on said upper end, an abutment extending upwardly on said casing for preventing movement of said arm from one side or the other of said predetermined position to the opposite side thereof, whereby to determine the hand of said closer, and said spring yielding to permit movement of said arm over said abutment, whereupon said arm may be moved to one side or the other of said abutment to change the hand of the closer.

4. In a door closer of the class described, a casing, a shaft rotating in said casing and having an upper end extending upwardly out of said casing, an arm fitted on the upper end of the shaft for rotation therewith, energy storing means adapted to be energized for returning a door to closed position, means interconnecting said shaft and said energy storing means for energizing said energy storing means upon rotation of said shaft and arm in either of opposed directions from a predetermined position relatively to said casing whereby said closer may be used on both left and right hand doors, a spring holding said arm on said upper end of the shaft, limit means in the form of a triangular abutment on said casing extending upwardly into the path of rotation of said arm with said shaft for holding said arm at one side or the other of said predetermined position relatively to said casing, whereby to determine the hand of said closer, and said spring yielding to permit movement of said arm above said limit means, whereupon said arm may be moved to one side or the other of said limit means to change the hand of the closer.

5. In a door closer of the class described, a casing, a closer mechanism within said casing including energy storing means for returning a door to closed position, means for securing said casing to the upper surface of a doorway at one side of a door, longitudinally spaced means extending above the top of said casing and engaging the upper surface of the doorway so as to hold the casing away from said upper surface of the doorway and provide a space between the casing and the upper surface of the doorway which is open at each side of said casing, an operating shaft connected to said mechanism in said casing and operable to energize said energy storing means upon rotation thereof in either direction, said operating shaft extending from the top of said casing into said space, an operating arm connected to said operating shaft and adapted to extend from said space on either side of said casing depending on the hand of the door on which the closer is to be used, and said arm being of a length that it may engage said longitudinally spaced means whereby rotation of said arm from a position in which said arm extends from said space on one side of said casing to a position in which said arm extends from said space on the other side of said casing is prevented and the hand of the closer is determined.

6. In a door closer of the class described, a casing, a closer mechanism within said casing including energy storing means for returning to door to closed position, means for securing said casing to the upper surface of a doorway at one side of a door, longitudinally spaced means extending above the top of said casing and engaging the upper surface of the doorway so as to hold the casing away from said upper surface of the doorway and provide a space between the casing and the upper surface of the doorway which is open at each side of said casing, an operating shaft connected to said mechanism in said casing and operable to energize said energy storing means upon rotation thereof in either direction, said operating shaft extending from the top of said casing into said space, an operating arm connected to said operating shaft and adapted to extend from said space on either side of said casing depending on the hand of the door on which the closer is to be used, said arm being of a length that it may engage said longitudinally spaced

means whereby rotation of said arm from a position in which said arm extends from said space on one side of said casing to a position in which said arm extends from said space on the other side of said casing is prevented and the hand of the closer is determined, and means connecting said arm to said shaft for limited upward movement whereby said arm may clear the top of said spaced means when the casing is detached from the doorway to allow rotation of said arm to a position in which said arm extends from said space on the other side of said casing 10 so as to change the hand of the closer without detaching the arm from said shaft.
